DESIGN FOR A CUFF LINK

Horatio Ben Smith, New York, N. Y.

Application April 10, 1941, Serial No. 100,300

Term of patent 3½ years

To whom it may concern:

Be it known that I, Horatio Ben Smith, a citizen of the United States, residing at New York, in the county and State of New York, have invented a new, original, and ornamental Design for a Cuff Link, of which the following is a specification, reference being made to the accompanying drawing, forming part thereof.

Figures 1 and 2 are views of opposite ends of a cuff link, showing my new design.

I claim:

The ornamental design for a cuff link, substantially as shown and described.

H. BEN SMITH.
